UNITED STATES PATENT OFFICE.

EUGENIJ VICTOROVITCH KOLBASSIEFF, OF CRONSTADT, RUSSIA.

TELEPHONE.

SPECIFICATION forming part of Letters Patent No. 518,059, dated May 1, 1894.

Application filed September 21, 1893. Serial No. 486,069. (No model.)

To all whom it may concern:

Be it known that I, EUGENIJ VICTOROVITCH KOLBASSIEFF, a subject of the Czar of Russia, and a resident of Cronstadt, in the Province of St. Petersburg, Russia, have invented certain new and useful Improvements in Magnetic Telephones, of which the following is a full, clear, and exact description, reference being had to the accompanying drawings, forming a part of this specification.

My invention relates to appliances for transmitting articulate and various other sounds, and more particularly to those appliances which utilize natural magnetism, as distinguished from such appliances as utilize electric currents for such transmission.

My invention is applicable to magnetic telephone systems generally, but it is also peculiarly adapted for submarine uses, such, for example, as in transmitting signals and messages of various kinds between divers at their work and their assistants at the surface of the water.

The primary objects of my invention include the production of a magnetic telephone which shall be very simple, compact and durable in construction, which shall serve both as a receiver and as a transmitter, and which, when serving as a transmitter, shall deliver articulate or other sounds both very loudly and very distinctly. Also to produce a telephone all of the essential operative parts of which shall be completely incased, so as to permit the instrument to be submerged in water without any possibility of injury or even impediment to its parts.

To the above purposes my invention consists in certain peculiar and novel features of construction and arrangement, as herein-after described and claimed.

The more precise nature of my invention will be better understood when described with reference to the accompanying drawings, in which—

Figure 1 is a front elevation of a magnetic telephone embodying my invention. Fig. 2 is a similar view of the telephone, but with its diaphragm-cap removed. Fig. 3 is a transverse section of the telephone, taken on the line 3—3 of Fig. 1. Fig. 4 is a transverse section of the telephone, taken on the line 4—4. Fig. 5 is a transverse section of a diver's hel-

met with a receiving and a transmitting instrument mounted therein.

In the said drawings, 1 designates the body or back portion of a magnetic telephone embodying my invention; this body or back portion being shown as of disk-shape with a circular margin 2 which is turned upwardly or forward to constitute a flange. This body or back 1 may be of wood, hard rubber, metal, or other suitable material, and to the margin 2 thereof is secured, by brazing or in any suitably tight manner, a circular front portion 3; the rear edge of this front portion 3 being shown as embracing the front edge of the marginal flange 2, and said front portion 3 being also shown as curved inwardly and forwardly and then extended directly forward, while the marginal flange 2 is shown as curved outwardly and forward transversely. To the inner surface of the front portion 3 is closely fitted a ring 4 which may also be of wood, hard rubber, metal, or other suitable material (as also may the front 3) and which is internally screw-threaded. Into this screw-threaded ring 4 is inserted an externally screw-threaded cap-ring 5 which is shown as of approximately L-shape in cross-section; the external screw-thread being formed upon the rear part of the ring, and the cap 6 being attached to the inwardly extending front portion of the ring 5 by screws 7, or by rivets or in any other suitable manner. The cap 6 may be of wood, hard rubber, metal, or other suitable material (as may also the cap-ring 5) and said cap is shown as of circular form, having a central concavo-convex portion 8, the concave surface of which is presented outward or forward, and through the middle or center of this concavo-convex portion 8 is formed an opening 9. Just back of the concavo-convex portion 8 of the cap 6, is placed a diaphragm 10, of thin sheet metal; the margin of said diaphragm being interposed between the inner or rear surface of the cap 6 and the front or outer surface of the cap-ring 5, and being securely retained in such position by the screws 7.

Within the casing or body-portion 1 are placed a suitable number of permanent horseshoe magnets 11 the extremities of the arms of which are adjacent to the center or middle of the casing and the bends of which are

adjacent to the outer margin thereof; said magnets being arranged in a circular series radiating outward from the center or middle of the casing. The rear inner ends of the magnet-arms are connected together by a disk or plate 12 which rests upon the front surfaces of said ends and which is connected to said ends of the arms by screws or rivets 13, and into the center of which is screwed, or otherwise closely secured, the rear end of a pole-piece 14; said pole-piece being shown as formed with a longitudinal or axial bore 15 opening at the front end of the pole-pieces and terminating within the rear end thereof, and the arrangement being such that there exists an uninterrupted magnetic contact from the rear arms of the magnets through the disk or plate 12 and pole-piece 14. Surrounding this pole-piece 14 is a second pole-piece 16 which is of opposite polarity from that of the pole-piece 14 and which is of tubular form, and also of such internal diameter as to leave an annular space between the outer sides of the pole-piece 14 and the inner surface of the pole-piece 16. The rear end of the pole-piece 16 has a continuous external flange 17, which rests upon the outer surfaces of the front arms of the magnets 11, at the inner ends thereof, and which is secured to said ends of the magnet-arms by screws 18, or rivets or other equivalent means. The space between the pole-pieces 14 and 16 is filled by a helix or coil 19 of insulated wire, of copper or other suitable conductive material the two strands 20 and 21 of which are combined to form an insulated line-cable 22; and this line cable being shown as leading outward through a thimble 23 on the flange 2 of the casing or back 1. Previous to their assemblage as the line-cable 22, the two strands 20 and 21 of the coil 19 are connected by two binding-posts 24 to a bridge-piece 25 which is of insulating material and secured, by attaching-screws 26, or other suitable means, to the outer arms of the magnets 11. A cap 27 is interposed between the front ends of the pole-pieces 14 and 16 so as to protect the coil 19, and at the opposite or remote end of the line cable 22 the two strands 20 and 21 of wire are preferably again separated and provided with sleeves or bonnets 28, so as to be connected to the binding-screws 24 of another and similar instrument.

For convenience in holding the instrument either in one of the user's hands, or within a diver's helmet, as will be presently explained, a handle 29 is shown as extending radially outward from one side of the casing 1, and said casing is also shown as provided with an external eye 30 by which the instrument may be hung upon a hook or nail when not in use.

In Fig. 5, I have shown an application of my telephone to submarine uses, 31 designating a diver's helmet, which may be of the usual or of any preferred type of construction, and within this helmet are shown two of the telephones embodying my invention; one of

the telephones being so placed as to be adjacent to the diver's mouth and to act as a transmitter, and the other telephone being so placed as to be adjacent to one of the diver's ears and to act as a receiver. These two instruments are shown as each retained in its proper position within the helmet by a spring clip or clasp 32 which embraces the handle 29; the clip or clasp for the transmitting instrument being shown as secured to the neck of the helmet, and the clip or clasp for the receiving instrument being shown as secured to one side of such helmet. Obviously, inasmuch as each instrument is capable of acting both as a receiver and transmitter, there may be but one instrument placed within the helmet or as many of such instruments as the exigencies of the service may demand and the capacity of the helmet permit. Furthermore either the clips or clasps 32 or any other suitable devices may be used for retaining the telephones in position within the helmet.

It is evident that the line-wires may be so arranged either as to connect each diver with a single assistant upon a float above the water, or so as to connect a diver with several assistants, or one or more assistants with one or more divers, and also that the divers may be connected communicatively each with the others. I desire to state, further, that the cap of each telephone may be packed with cotton-wool or other equivalent material, to further deaden any sounds which would interfere with the proper working of the telephones, and also that the internal surfaces of the casing of each telephone may be coated with a suitable rubber composition, so as to prevent any harmful effects of moisture within the instrument.

In Fig. 5 the line-wires from the two telephones are shown as carried through the inlet and outlet pipes 34 for air, and said pipes are also shown as containing within their sockets bristled wires to act as sound-deadeners, but these latter devices form no part of my present invention.

Having thus described my invention, what I claim as new therein, and desire to secure by Letters Patent, is—

1. A magnetic telephone, comprising a containing casing, a plurality of permanent horseshoe magnets all arranged wholly within the casing and wholly in a common interior plane transverse to the center of said casing, and also in radial relation to said center and furthermore with the ends of their arms adjacent to said center, a central pole-piece structurally connected to one arm of each magnet, a cylindrical pole-piece surrounding the central pole-piece and of opposite polarity therefrom and also structurally connected to the opposite arm of each magnet, and a conductive coil interposed between the two pole-pieces and surrounding the central piece, substantially as set forth.
2. A magnetic telephone, comprising a containing casing, a plurality of permanent horse-

shoe magnets all arranged wholly within said casing and wholly in a common interior plane transverse to the center of said casing, and also in radial relation to said center, and furthermore with the extremities of their arms adjacent to said center, a central pole-piece structurally connected to one arm of each magnet, a cylindrical pole-piece of opposite polarity from said central pole-piece and surrounding the same and also structurally con-

nected to the opposite arm of each magnet, a conductive coil surrounding the central pole-piece between the latter and the cylindrical pole-piece, and a diaphragm overlying the outer ends of said pole-pieces, substantially 15 as set forth.

EUGENIJ VICTOROVITCH KOLBASSIEFF.
